UNITED STATES PATENT OFFICE.

LOUIS G. DE KERMOR, OF EDMONTON, ALBERTA, CANADA, ASSIGNOR TO DELWAY HEATERS, INC., OF NEW YORK, N. Y., A CORPORATION OF NEW YORK.

STEAM ATOMIZING OIL BURNER.

Application filed August 18, 1927. Serial No. 213,721.

This invention relates to oil burners and my improvements are directed to devices of this character wherein steam is employed as the atomizing agent for oil delivered by 5 the burner.

One of the objects of my invention is to provide a burner structure wherein steam is caused to envelop the passage through which oil passes to the oil delivery tip, in 10 order that the oil may thus become highly heated just prior to its issuance from said tip. Another object consists in the provision of means causing steam to impinge upon the stream of oil issuing from the oil 15 delivery tip, to atomize the oil and effect a commingling of the oil and steam just prior to emission of the mingled fluids from the burner nozzle for flame production, and still further objects are comprised in the novel 20 structure and arrangement of parts whereby the quantities of oil and steam flowing through the burner may be conveniently regulated.

Other features and advantages of my invention will hereinafter appear.

In the drawing:

Figure 1 is a side sectional elevation of my improved burner.

Fig. 2 is a section on the line 2-2 of 30 Fig. 1.

Fig. 3 is a section on the line 3-3 of Fig. 1, and

Fig. 4 is a section on the line 4-4 of Fig. 1.

In said views let 1 indicate the burner body, which is tubular in form, with open ends, and having an angular offset 2. The rear end of the tubular body is provided with an external thread adapting it to receive a 40 closure cap 3, while the forward portion of said tubular body is of reduced external diameter, threaded to receive a nozzle member 4. The tubular body 1 is interiorly threaded at its rearward portion to receive a screw plug 5 that is of reduced external diameter at its forward portion to thereby provide an annular clearance 6 between said plug and tubular body, the forward end of said plug being screwed into a circular 50 block 7 that fits closely within the forward end of the tubular body, said block having a series of longitudinal grooves 8 extended therethrough.

The plug 5 is axially pierced with a tubu- 55 lar passage-way 9 and contains a valve stem

10 having a rearward shank portion 11 that is threaded through the rearward portion of the plug, for adjustment purposes, said valve stem carrying a valve 12 at its forward end, lying in a forward extension 13 of block 60 7, which has a conoidal portion 14 to co-act with said valve, said extension 13 thence continuing into a cylindrical oil delivery tip 15. The shank portion 11 of the valve stem is provided with a head 16 by which the valve may be adjusted, said head 16 lying in a recess 17 provided therefor in the end of plug 5, where it is readily accessible upon removal of cap 3.

It will be noted that the offset 2 is provided with a relatively large passage-way 18 and a smaller passage-way 19, the passage-way 18 being in communication with the clearance 6 in the tubular body 1, and the passage-way 19 communicating, through an orifice 20 in plug 5, with the passage-way 9.

Oil is supplied to the passage-way 9 through passage-way 19, and steam enters clearance 6 from passage-way 18, serving thereby to heat the oil flowing through the burner, and thence performing the further function of atomizing the thus heated oil issuing from the delivery tip 15.

The offset 2 is shown as provided with a flange 21, in bolted relation with the flange 22 of a connection 23 having passage-ways respectively for oil and steam derived from suitable sources, not shown. The nozzle member 4, hereinbefore referred to as screwed upon the reduced, forward portion 90 of the tubular body, has an axial opening therethrough characterized by these contours: the inward portion 24 of said opening, which is co-extensive with the extension 13 of block 7, has conoidal form complementary to that of said extension, there being an annular space 25 left between the opposed conoidal surfaces, which space is regulable in extent by adjustment of the nozzle member, to thereby control the passage of steam 95 delivered thereto through the grooves 8 for oil atomizing and commingling purposes.

Forwardly of said conoidal portion 24 the axial opening has a cylindrical portion 26, the oil delivery tip 15 lying clearly within this portion, while in advance of said cylindrical portion said axial opening is outwardly flared, as at 27, to permit spreading of the atomized fuel.

The oil control valve 12 is forwardly ta- 110

pered at 28 to coincide with the internal taper of extension 13 to thus control the quantity of oil permitted to pass said valve accordingly as said valve is advanced or retracted. Rearwardly of the tapered portion 28 the valve has the cylindrical portion 29 with longitudinal clearances 30 formed therein for oil flow, this feature being more clearly shown in the enlarged view of Fig. 2. 10 Variations within the spirit and scope of my invention are equally comprehended in the foregoing disclosure.

I claim:

1. An oil burner comprising a tubular body portion, a plug having an oil passage and a forwardly reduced portion cooperating with said body portions to define a steam passage, a block carried by said plug and having a series of longitudinal grooves and having a 15 forwardly extending conoidal portion, a nozzle carried by said body portion and having a central opening spaced from but conforming to the contour of said conoidal portion and a valve operating in said oil passage and 20 presenting a series of longitudinal clearances 25

opening toward the central opening of said nozzle.

2. An oil burner comprising a tubular body portion, a plug having an axial bore forming an oil passage receivable therein and having a forwardly reduced portion to provide an annular clearance between said plug and body portion for the passage of steam, a burner nozzle having a tapered opening carried by said body portion, a block attached to the forward end of said plug and having a bore forming a continuation of the axial bore of the latter, said block having a series of longitudinal grooves extended therethrough and establishing communication between said annular clearance and the burner nozzle, said block further having a forward conoidal portion spaced from the walls of the tapered opening of said nozzle, and an adjustable valve disposed within the bore of said block and embodying a head portion having a series of longitudinal clearances therein. 30 35 40 45

New York, August 8th, 1927.

LOUIS G. DE KERMOR.
